UNITED STATES PATENT OFFICE.

EDWARD L. DUNKLE, OF EAST BRADY, PENNSYLVANIA.

SNOW-REMOVING APPARATUS.

Application filed August 28, 1925. Serial No. 53,058.

To all whom it may concern:

Be it known that I, EDWARD L. DUNKLE, a citizen of the United States, and a resident of East Brady, in the county of Armstrong and State of Pennsylvania, have invented a new and useful Improvement in Snow-Removing Apparatus; and I do hereby declare the following to be a full, clear, and exact description thereof.

10 My invention relates to apparatus for use in removing snow from railway tracks, city streets, and highways.

One object of the invention is to provide an improved form of apparatus which may 15 be conveniently embodied in or applied to an ordinary railroad flat car, a motor driven trolley car, or an automobile truck.

Another object of my invention is to provide a device of the character referred to 20 having a scoop which is adapted to remove a relatively wide section of snow at curves, to provide greater clearance at such points so that movement of vehicles will not be restricted when passing around such curves.

25 Another object of my invention is to simplify and improve generally the structure and operation of devices of the character referred to.

One form which my invention may take is 30 shown in the accompanying drawing, wherein Fig. 1 is a side elevational view of apparatus embodying my invention; Fig. 2 is a similar view, partially in section; Fig. 3 is a plan view of the apparatus; Fig. 4 is a 35 front elevational view, on an enlarged scale, of the steam jet pipes by means of which the snow is melted, and Fig. 5 is a view, on a still further enlarged scale, of one of the jets.

40 Referring to Figs. 1 and 2, I have shown the apparatus as mounted upon a platform or flat body 6 that is supported by car trucks 7, this portion of the apparatus having the form of an ordinary flat car. A shaft 8 extends through the platform 6. This shaft 45 at each end pivotally supports one of the longitudinal frame members 9 which are connected at their rear ends by a cross frame 10 and at their front ends are offset downwardly as indicated at 11, to provide a seat for a scoop 12. A cross bar 14 is secured to the platform 6 by bolts or otherwise. Uprights 15 and booms 16 are secured to the cross bar 14. Braces 17 and 18 are provided 50 for the booms 16. A bracket 19 extends rearwardly from the cross bar 14 and supports a

swivel nut 20 through which an adjusting screw 21 extends. The lower end of the adjusting screw 21 has swivel connection with a pivoted block 22 that is connected to the 60 transverse bar 10 that is secured to the rear ends of the pivoted bars 9. As the screw 21 is rotated, it will be seen that the bars 9 are moved about their pivot 8 to raise or lower the scoop 12, so that such scoop may 65 be positioned at any desired height above the surface of the ground. The ends of the cross bar 14 are turned downwardly as indicated at 14^a, to serve as vertical guides for the pivoted bars 9, such downturned 70 ends being bifurcated, if desired.

A yoke 24 of general U-form engages the bottom and sides of the scoop 21 and its upper leg portions are connected to cables 25 that extend over guide sheaves 26 and 27 75 carried by the booms 16 and the uprights 15, respectively. The rear ends of the cables 25 are connected to counterweights 28 that are centrally recessed so that they slide on vertical pins 29 which are secured to the 80 bracket 19. These pins 29 serve to prevent swaying or swinging of the counterweights. The weights 28 counterbalance the scoop 12 and the parts carried thereby, to remove excessive weight from the forward end of the 85 car or truck upon which the apparatus may be mounted, particularly when heavy snow is encountered.

The scoop is provided with a wing 30 at 90 each forward vertical edge, that is connected to the body portion by hinges 31. Each wing 30 is provided with a horizontal portion 30^a, such portions overlapping one another, as shown by dotted lines in Fig. 3. A bottom sheet 32 overlies the portions 30^a and is provided with a ridge or hump 32^a, behind which the melted snow may be accumulated for a purpose to be hereinafter described. The extensions 30^a of the wing portions are necessary in order to provide a continuous 95 bottom for the scoop, when the wings are expanded as shown in Fig. 3. In removing snow at curves, it is usually desirable to make a wider cut than along straightaway track, so that clearance will be provided to 100 permit cars to pass freely around the curve. The hinged mounting of the wings 30 permit of such widening of curves, since they can be swung to flared position by means of bell cranks 33 that are 105 operated by pull rods 34 and hand levers 35. Sector-shaped guides 36 are provided for the 110

levers 35 and such levers may be locked in either forward or rearward positions by pins 37 that may be inserted when the lever is in its forward position or when it is in 5 its rearward position, as may be desired.

The scoop 12 is provided with a hood portion 39 that is slotted vertically at 40 so that it may normally closely lie against the wings 30 but may yield to permit outward movement of such wings. Also, the forward edge 10 of the hood 39 may be flared upwardly so as to encompass a greater quantity of snow.

Heat for melting the snow caught within the scoop 12 is supplied from a steam boiler 42 that is mounted upon the flat car. The boiler may be heated by oil burners or other suitable fuel. A pipe 43 is connected to the steam space at the upper end of the boiler, through a swivel joint 44 of any suitable 20 form and directs the steam through pipes 45 and 46 (Fig. 2) to pipes 47 and 48 (Fig. 4) that are provided with jets 49 (Fig. 5). Steam issuing through these jets, under pressure, melts the snow within the scoop. The 25 snow water collected behind the ribs 33 may be utilized, so far as needed, for supplying the boiler 42, with water, to replace that which has been converted into steam. Surplus water may be conveyed from the scoop 30 to a ditch at the side of the road, in any suitable manner.

The boiler 42 may not have sufficient heating capacity to melt larger quantities of snow, and I therefore provide an additional 35 heating unit for supplementing the boiler 42. This heating unit consists of a superheater 50 that is preferably mounted upon the interior of the scoop and against the rear wall thereof. An oil burning system 40 51 is connected to the superheater to supply the necessary heat, through burner nozzles 52. This fuel burner unit could also be utilized to supply fuel for the boiler 42.

Steam from the boiler 42 is conducted, 45 through pipes 53 and 54 to pipes 55 and 56, respectively, that communicate with the superheater at opposite sides thereof. The pipe 53 (Fig. 1) is connected through a swivel joint 57 with the steam space in the 50 top of the boiler 42. The pipe 54 is similarly connected, through a swivel coupling 59, at the opposite side of the boiler 42. The steam which enters the superheater 50 is thereafter conducted through a pipe 60 to 55 tubes 61 (Fig. 4) that are provided with nozzles as indicated at 49 in Fig. 5. Steam for melting the snow may be supplied simultaneously through the pipes 47, 48 and 61 or either set of pipes may be used to the 60 exclusion of the other. When only pipes 47 and 48 are to be used, communication between the boiler 42 and the superheater 50 may be shut off by suitable valves, while communication between the boiler 52 and 65 pipes 47 and 48 may be cut off and all of the

steam from boiler 42 directed to the superheater and thence to the pipes 61.

I claim as my invention:

1. Snow-removing apparatus, comprising a vehicle, a frame pivotally supported upon said vehicle, a scoop carried at the forward end of said frame and having a rear wall, means for adjusting said frame about said pivot, a boiler mounted upon said vehicle, heating pipes mounted within said scoop, a steam line connecting said boiler and said heating pipes, a combustion heater mounted in said scoop and adjacent to the rear wall thereof, means for supplying fuel to said heater from a point rearwardly of said wall, a second series of heating pipes in the scoop, a pipe connection between said boiler and said combustion heater, and a connection between said combustion heater and said second series of heating pipes. 75 80 85

2. Snow-removing apparatus comprising a framework and means for mounting the same upon a vehicle, a scoop having a body portion whose side walls are each vertically divided, a hood having flexible side walls overlapping the upper portions of the side walls of the body portion and of yieldable material, and means for moving the forward side sections laterally of the scoop in order to vary the width of the mouth of the scoop. 90 95 100

3. Snow-removing apparatus, comprising a framework and means for mounting the same upon a vehicle, a scoop having a body portion whose side walls are each vertically divided, a hood having flexible side walls overlapping the upper portions of the side walls of the body portion and of yieldable material, and means for supplying heat to the interior of said scoop. 100 105 110

4. The combination with a vehicle, of a supporting member disposed longitudinally of said vehicle and pivotally connected thereto intermediate its ends, a scoop supported by the forward end of said supporting member, a beam connected to said vehicle and extending substantially parallel to said supporting member, an upright adjacent to the other end of said supporting member, guiding sheaves carried by the outer end of said beam and said upright, respectively, a cable passing over said sheaves and having one of its ends connected to the forward end of said supporting member, and a vertically adjustable connection between the other end of said cable and the vehicle. 115 120 125

5. The combination with a vehicle, of a supporting member disposed longitudinally of said vehicle and pivotally connected thereto intermediate its ends, a scoop supported by the forward end of said supporting member, a beam connected to said vehicle and extending substantially parallel to said supporting member, an upright adjacent to the other end of said supporting member, guiding sheaves carried by the outer end of said 130

beam and said upright, respectively, a cable passing over said sheaves and having one of its ends connected to the forward end of said supporting member, and a vertically adjustable connection between the other end of said cable and the vehicle, the forward end of said supporting member being

depressed vertically for supporting the scoop in substantially horizontal alignment with the vehicle.

In testimony whereof I, the said EDWARD L. DUNKLE, have hereunto set my hand.

EDWARD L. DUNKLE.
